UNITED STATES PATENT OFFICE.

JOHN LUTHER, OF ST. JOSEPH, MISSOURI.

PORTABLE SINK.

SPECIFICATION forming part of Letters Patent No. 274,952, dated April 3, 1883.

Application filed December 9, 1882. (Model.)

To all whom it may concern:

Be it known that I, JOHN LUTHER, a citizen of the United States, residing at St. Joseph, in the county of Buchanan and State of Missouri, have invented certain new and useful Improvements in Portable Sinks; and I do hereby declare that the following is a full, clear, and exact description of the same, reference being had to the annexed drawings, making a part of this specification, and to the letters and figures of reference marked thereon.

Figure 1 of the drawings is a perspective view of my invention, and Fig. 2 a longitudinal vertical section of the same.

This invention relates to certain new and useful improvements in kitchen-furniture; and its object is to provide such a piece of furniture for kitchen usage whereby a sink, dish-drainer, and bread-board may be combined in one article to economize space, and at the same time the whole be readily removed from one place to another. These objects I attain by the construction substantially as shown in the accompanying drawings, and hereinafter described.

In the drawings, A represents a wall or support, to which is suitably secured an upright frame, consisting of standards *a*, connected by a spatter-board, B, of a width equal to or greater than that of the sink C; or the standards *a* may be entirely dispensed with and the frame composed entirely of one piece. The sink-box C in this instance is hinged to the standards *a*, and is provided with a dish-drainer, D, pivotally connected between its sides, to admit of its being folded or closed in the sink-box when not in use as a drainer, the under face of its bottom being plain to admit of its use as a kneading or bread board, though it is obvious that the same may be used as an ordinary table when in its closed position. The upper face of the drainer-bottom is provided with flutes or corrugations *b*, in order that the water from the dishes, &c., may be more readily carried off, that end of the sink-box C upon which the drainer rests when opened out being cut away a sufficient distance to give said drainer a firmer rest and decrease of its inclination. The sink-box C is also provided

with the usual waste-pipe connection, *c*, and plug or stopper *d*. To the connection *c*, when the sink is in use, is fitted a removable waste-pipe, E, having its bore of a tapering form in order to insure a tight joint. The sink-box, 55 when open for use, is supported at each end by a wrought-iron or other suitable brace, F, extending from the bottom of the upright frame to nearly the outer side of said sink-box. These braces or supports are bent in the manner substantially as shown at *e*, Fig. 1, in order to give additional strength and prevent their extending out from the frame below the sink when closed, and are provided at their upper ends with cross-heads or buttons, which work 60 in slots *f* in the ends of the sink-box, said slots being widened at their rear ends to admit these cross-heads or buttons.

When the sink or its attachments are not required for use, the drainer D is folded into the box, the waste-pipe E removed, and, if desired, also placed in the box, and the whole swung up against the spatter-board B, as shown by dotted lines, Fig. 1, a spring-catch, hook, or other locking device, *g*, upon said spatter-board engaging with the outside of the sink-box to retain it securely in this position out of the way, thereby economizing space and admitting of a chair, table, or other article being placed in the space occupied by the sink when 75 in position for use.

Having now fully described my invention, what I claim as new, and desire to secure by Letters Patent, is—

In a portable sink, the stationary spatter-board B, having pivoted thereto the curved supports or braces F, in combination with the folding sink C, the dish-drainer D, pivoted in the sink-box, as set forth, and removable waste-pipe E, the outer ends of the supports or 85 braces adapted to work in slots *f* at the ends of the sink-box, substantially as and for the purpose specified.

In testimony that I claim the above I have hereunto subscribed my name in the presence 95 of two witnesses.

JOHN LUTHER.

Witnesses:

JOHN S. CROSBY,
WM. H. FLOYD.
